[57] CLAIM

The ornamental design for a container for artists' materials or similar articles, substantially as shown and described.

DESCRIPTION

FIG. 1 is a perspective view of a container for artists' materials or similar articles showing my new design;
FIG. 2 is a rear elevational view thereof, an intermediate portion of the carrying strap being omitted for convenience of illustration;
FIG. 3 is a left side elevational view thereof; and
FIG. 4 is a top plan view thereof.
